Madison, Wis.

Application November 17, 1937, Serial No. 174,954

3 Claims. (Cl. 126—364)

This invention relates to a heating attachment for household or other water supplies, having for its purpose to utilize waste heat and partially or wholly warm the water of such supply.

The invention has for its object to provide a system utilizing waste heat for the purpose stated, which will operate with efficiency without detracting from the efficient operation of the boiler or furnace to which it is applied, and which will 10 of itself be of simple and durable construction and rendered applicable to the existing boiler or furnace with a minimum of disarrangement of the latter.

Heretofore, numerous adjunctive devices have 15 been made and used for the transfer of a portion of the heat of a boiler or furnace to water stored for household and other uses. Some of these devices involved the use of heat-absorbing coils located within the firepot or combustion chamber of the heating plant, but such arrangements are not economical in that they exercise a disadvantageous influence over the combustion relied upon for the main purpose of the plant. Other arrangements have been located in the vent flue 20 where the heat transfer surfaces are impinged against by the stream of products of combustion with the disadvantage of imposing some obstruction upon the flow of the latter as well as causing precipitation of matters borne in suspension 25 therein.

The present invention proceeds upon the principle of associating with a vent flue which extends from the combustion chamber to the chimney or stack, a heat transfer chamber related to such flue as a dead end offset communicating with the flue without offering any obstruction to the latter and in a position to freely admit the products of combustion under their own levity into the presence of heat absorbing surfaces, 30 from which, after giving up a portion of their heat, the cooled products settle by gravity back into the flue, where they pass off to the chimney. In the preferred arrangement, the flue is constructed with a portion of its length directed upward and a portion extending from said upwardly directed portion laterally, for instance, after the manner of an elbow commonly used in such flues; and the dead end heat transfer chamber communicates with the flue at the point of deflection 35 between these two portions so that hot products of combustion can rise into the heat transfer chamber by a movement which is a continuation of its upward flight in the flue, and preferably also the return from the heat transfer chamber of 40 products of combustion, with the heat partially

dissipated, will reach that portion of the flue which has been deflected from the uptake portion.

Finally, the device contemplates the use of a 5 damper or other suitable valve located at the communication between the dead end heat transfer chamber and the flue, and this damper is arranged to be regulated in position for the purposes, first, of regulating the volume of hot products of combustion that rise into the heat transfer chamber, and secondly, to direct the intake and discharge of these hot products in a manner to favor their circulation through the said chamber. Thus, if a damper be mounted at the lower end of the heat transfer chamber, with 10 movement upon a horizontal axis transverse to the axis of the flue, and this damper be adjusted with its lower margin forward in the direction of flow through the flue, a relatively wide opening will be presented on the intake side of the damper immediately over the uptake portion of the flue, while the said lower forwardly presented margin of the damper will provide a deflecting surface directing return products toward 15 the chimney and thus promote their evacuation 20 from the heat transfer chamber through the ejecting or suction effect of the main flow of products in the lateral portion of the duct.

Referring now to the accompanying drawing showing two embodiments of the invention by way 25 of illustration—

Figure 1 is a front elevation showing a furnace 30 domestic water storage tank, which may be provided with its own normal gas heater; also a chimney and auxiliary heater associated with the 35 smoke duct leading from the furnace to the chimney.

Figure 2 is a front elevation showing a portion 40 of the smoke duct together with the heat exchange chamber, auxiliary heater and its damper control.

Figure 3 is a cross section at right angles to 45 and showing portions of Figure 2.

Figure 4 is a diagrammatic view showing the 50 auxiliary heater associated with an inclined smoke duct between the furnace and the chimney; and

Figure 5 is a detail view showing a modified 55 form of heat exchanger in the auxiliary heater.

A represents the conventional type of furnace or boiler, B a stack or chimney, and C, C', C" several sections of a flue delivering products of combustion from the furnace to the chimney. D represents a heat transfer chamber having a closed end D' that makes it a dead end chamber, 55

communicating with the flue at the point X and preferably that portion C' thereof which is directed upwardly and from which hot products of combustion may flow into the chamber D without changing their direction, so as to promote the entry of hot products in the said chamber. Chamber D contains a heat absorbing water coil E connected in the conventional manner through intake pipe E' and return pipe E2 of any suitable source of hot water storage. Chamber D also contains a damper F mounted upon a supporting and controlling shaft F' that is transverse to the axes of the flue and heat transfer chamber. Damper F may be rotated upon its shaft F' through means of a crank arm F2 cooperating with an arcuate register, and its movement is preferably such that when partially closed to restrict flow of hot products of combustion into the heat transfer chamber, it will present an upwardly converging opening G at the right hand side of the drawing, which will promote entry of the heating medium while its lower marginal portion will be inclined forwardly toward the out-flow portion C2 of the flue and provide a directed discharge G' that promotes delivery of the partially spent hot gases in the direction of flow toward the chimney B.

As shown in Figure 4, the auxiliary heater may be incorporated with an inclined smoke duct Cr in such position that the products of combustion can rise vertically into the heat exchange chamber Dr; and, as suggested in Figure 5, other suitable forms of heat absorbing water container Ex may be located in the heat transfer chamber Dy in lieu of the coil shown in Figures 1, etc.

In addition to determining the volume of hot gases that rise into the heat exchange chamber, the damper divides the inflow from the outflow in a manner to develop a partial by-pass effect and creates much less eddy current disturbance of the draft on the furnace than if the damper were omitted. And when the damper is inclined to a substantial angle to reduce the volume of inflow by the spacing of the upper margin of the damper from the wall of the chamber, smoothness of inflow is promoted notwithstanding the selected constriction of the throat; and this smoothness of action and resultant minimum of eddy current disturbance in the draft is further augmented by the deflecting influence of the lower end of the damper, and its definite presentation of the cooled gases in the direction of flue current toward the chimney promotes circulation through the chamber. This circulation or smoothness of flow is still further promoted by the ejector relation of the flue current to the cooled gas discharge.

We claim:

1. In auxiliary heating apparatus for boilers and furnaces, the combination of a combustion

chamber discharge duct having an unobstructed flow capacity from the combustion chamber to a chimney or flue, said discharge duct being directed for a portion of its length upwardly and deflected thence laterally, a dead end heat exchange chamber opening laterally into said duct at the point of deflection and extending upwardly from said duct, said chamber receiving a portion of the products of combustion by continued upward flow thereof and returning said products of combustion after extracting heat therefrom, to said duct, and said heat exchange chamber containing suitable heat absorbing surfaces capable of utilizing the heat so absorbed.

2. In auxiliary heating apparatus for boilers and furnaces, the combination of a combustion chamber discharge duct having an unobstructed flow capacity from the combustion chamber to a chimney or flue, a dead end heat exchange chamber opening laterally into and extending upwardly from said duct at an intermediate point therein, said chamber receiving hot products of combustion from said discharge duct and returning said products of combustion, after extracting heat therefrom, to said duct, said heat exchange chamber containing suitable heat absorbing surfaces capable of utilizing the heat so absorbed, and said heat exchange chamber being provided with means governing the inflow capacity of its communication with said duct, said means comprising an angularly adjustable damper and means for selectively positioning the same, which said damper, by its adjustment, presents an upwardly contracting intake and a downwardly and forwardly presented discharge for the products of combustion.

3. In auxiliary heating apparatus for boilers and furnaces, the combination of a combustion chamber discharge duct for directing hot products of combustion from the combustion chamber to a chimney or flue, a dead end heat exchange chamber opening laterally into and extending upwardly from said duct at an intermediate point therein, heat absorbing surfaces disposed in said chamber and being capable of utilizing heat absorbed from said hot products of combustion, said dead end heat exchange chamber receiving said hot products of combustion from said discharge duct and returning said products of combustion, after extracting heat therefrom, to said discharge duct, and a damper for directing said hot products of combustion into said dead end heat exchange chamber, said damper being so disposed that said products of combustion enter said dead end heat exchange chamber on one side of said damper and are discharged therefrom on and in contact with the other side of said damper.
